UNITED STATES PATENT OFFICE.

LEUIG CHEW AND WILLIAM FREDERICK JENNINGS, OF LONDON, ENGLAND.

COMPRESSION PUMP.

Application filed December 9, 1922. Serial No. 605,798.

To all whom it may concern:

Be it known that we, LEUIG CHEW and WILLIAM FREDERICK JENNINGS, subjects of the King of Great Britain, and residents of 5 London, England, have invented certain new and useful Improvements in Compression Pumps, of which the following is a specification.

This invention relates to improvements in 10 that class of compressor or compression pump as used for refrigerating machines and particularly has reference to the construction of the top side of the piston or cylinder head wherein a plurality of ring valves are housed.

It is important with the high speed now adopted with this class of compressor that a maximum provision of valve area is obtainable both with the suction valves situated in the head of the piston and in the delivery valves situated in the yielding head or cover of the compressor cylinder. Besides it is important that there should be as few loose parts as is possible to avoid the 25 chance of any of such parts as for example split pins, nuts and the like when dislocated dropping into the cylinder.

The object of the present invention is to 20 so house and construct such valves that positively no loose parts can be dislocated and therefore a maximum speed of the compressor obtained without fear of accident and consequently the efficiency of the machine both as regards suction and delivery 35 of the gas increased.

For the purpose of this description it will suffice to describe our invention as applied to the suction valves of a compressor which are housed in the top of the compressor piston but as will be evident the improvements 40 herein after set out are equally applicable to the delivery valves housed in the yielding head or cylinder cover of the machine.

Firstly in order to secure the maximum 45 valve area of any given piston the surface available is most effectively divided into seven circular valves of equal diameters, one situated in the centre and the other six disposed equi-distantly from and around the 50 central valve.

In carrying out our invention this disposition of valves is adopted and the several valves are housed in a disc or plate secured to the top of the piston by means of 55 six valve cover plates with depending stems

that are screwed into tapped holes provided in the head of the piston so that the said disc or plate that forms the housing for the several ring valves becomes a component part of the head of the piston. 60

Each of the valve cover plates aforesaid is duodecagonal in shape. The central valve which is similarly formed is provided with a valve cover plate the stem of which passes through the aforesaid disc or plate 65 and is secured to the underside thereof with a spring interposed so that it is free to be lifted for the purpose hereinafter described.

The central valve cover plate is primarily 70 constructed hexagonal in form and provided with duodecagonally disposed projecting flats on its corners which on being turned into position serve as locking means for the valve cover plates of the six valves surrounding the same. 75

These projections likewise serve for maintaining the central valve cover plate when raised in such a position as to permit of the removal of the several valve cover plates around the same, suitable upstanding studs 80 or projections being automatically left on the disc or plate by the act of machining out the several housings for the seven valves by the intersection of the seven circular borings by which said housings are formed. 85

The central valve cover plate is provided on its upper surface with a screwed stem to 90 which is applied a tool with a handle that projects beyond the top of the cylinder to facilitate the manipulation of the same. 90 The same tool which is provided with two depending pins also serves the purpose of releasing the several valve cover plates situated around the central valve, the said pins engaging with the perforations 95 provided to allow of a free gas discharge to the top side of the piston.

Given a piston head constructed as above described certain difficulties in regrinding the valves in position are consequent and these difficulties are overcome by the use or application of a circular spring clip which automatically holds the ring valve in position whilst a removable tapered plug with a handle on the top and a stem beneath that 100 fits the bore which normally contains the stem of the valve cover plate, affords a convenient tool for centering the valve in its true position for regrinding. 105

In order that our invention may be readily 110

understood reference may now be had to the accompanying two sheets of drawings in which—

5 Figure 1 is a sectional elevation of the top of a piston constructed in accordance therewith.

Figure 2 a plan view of the piston head.

10 Figure 3 is an enlarged sectional view of a portion of the disc or plate of the piston showing the application of the valve holder or regrinding tool.

Figure 4 is an elevation of the stem or handle of the tool.

15 Figure 5 a plan of the circular spring grip and

Figure 6 an underside view of the ring valve.

Similar reference characters relate to like parts in all the figures of the drawing.

20 Referring now to Figures 1 and 2 in which are illustrated our improvements applied to the suction valves carried in the head of the piston it will be seen on reference to the plan (Figure 2) that the disc or plate 2 is provided with six borings or 25 housings 3 on the base of which are provided the seatings 4 with which the ring valves 5 contact. The several housings 3 are disposed hexagonally around the central 30 housing 6, which in fact by the intersection of the several housings consists of the six more or less triangular studs 7 that serve the purpose of maintaining the central valve cover plate in its raised position as previously referred to.

35 The plate 2 is secured to the top of the piston 8 by the screwed stems 9 that depend from the valve cover plates 10. The central valve cover plate 11 has a stem 12 that passes 40 through the disc or plate 2 and is secured to the underside thereof by means of the nut 13 with the spring 14 interposed so as to allow the said plate 11 to be lifted as hereinafter described.

45 Each of the valve cover plates 10 are duodecagonal in form and when in their normal position as seen in Figure 2 they are locked by the interconnection of the projecting members 15 provided on the central valve cover plate 11, and the several valve cover plates 10 are thereby retained in position having been screwed into their respective tapped holes in the top of the piston 8. It will be seen that the central valve cover 55 plate 11 is mainly hexagonal in form with projecting members 15 duodecagonally disposed so as to agree with the sides or edges of the several valve cover plates 10, such edges being normally on the same plane as 60 seen in Figure 1.

65 In order to remove one or other of the several valve cover plates 10 the central cover plate 11 is provided with a screw-stud 16 with which is engaged the tool 17 the spindle 18 of which carries a handle and

extends upwardly preferably beyond the top surface of the cylinder 19.

Given a tool or spanner 17 applied as shown in Figure 1, the central valve cover plate 11 can be raised and turned so that the projections 15 rest upon the top of the studs 7 and in this position the hexagonal edges 20 of the central valve cover plate 11 are disposed diametrically of the valve cover plates 10 so that on removal of the tool 17 75 from the stud 16 and the application thereof to the top side of the valve cover plates 10, by the engagement of the depending pins 21 with the holes 22 bored through the top of said valve cover plates each individual valve cover plate 10 can be removed from the top of the piston 8 and upon the removal of the six stems 9 the valves 5 can be taken out and the top disc or plate 2 removed from the top of the piston 8, when the central valve cover plate 11 can also be removed by unscrewing the nut 13.

Beneath each of the cover plates 10 and 11 is provided the boss or guide 23 for the retention of the ring valves 5 in their correct position, this boss 23 is divided into several projecting points 24 by reason of the borings 22 thus reducing the frictional contact of the ring 5 with its guides to a minimum.

The admission of gas to the top side of 95 the piston takes place through the holes 25 which are circularly disposed beneath the ring valves 5 and finds its way past the valve 5 to the top side of the piston through the holes 22 and the space between the edge of 100 the valve cover plates 10 and the housings or borings 3.

A thin fibre washer 35 may be inserted between the underside of the boss 23 and the contacting surface of the disc or plate 2 to 105 ensure a gas-tight joint and afford a means of adjusting the relative position of the side that co-acts with the projecting member 15 of the central valve cover plate 11 by which it is locked or prevented from rotating.

110 Referring now to Figures 3 to 6, presuming one of the valves 5 requires to be reseated or ground in position the valve cover plate 10 is removed and the valve 5 placed on the spring holder or cylinder 26 which is provided with a flange 27 and is expanded by a cone 28 mounted on the stem 29 that carries the handle 30 the underside of the cone 28 carrying a circular dependence 31 which exactly fits the bore 32 which is normally occupied by the part 33 of the screwed stem 9 of the valve cover plate 10 when the valve is assembled in its housing 3. It will be understood that with a moderate amount of pressure applied to the handle 30 the valve 120 5 will be exactly centered and coincident with the valve seatings 4 in the respective housings 3 of the disc or plate 2 that forms the head of the piston. The valve holder or cylinder 26 is of the usual construction pro- 125 130

vided with the ordinary saw-cuts 34 in order to secure even expansion on the insertion of the cone 28, and afford a gripping effect on the ring 5.

5 Obviously the aggregate areas of the holes 22 and the annular spaces within the housings 3 are made of such dimensions as to at least equal the combined areas due to the lift of the several ring valves 5 so that a free 10 discharge of gas is ensured into the cylinder on each descent of the piston and by the disposition of the valves as aforesaid the maximum available valve area is obtained proportionately to the diameter or area of the 15 piston so fitted.

The component parts of the six outer valves being identical they are readily interchangeable.

What we claim is:—

20 1. In a compression pump, in combination, a plurality of ring valves, one of said valves being centrally disposed with respect to the remaining valves that are disposed equi-distantly from and around said central valve, a disc formed with a central housing for said central valve and similar housings disposed equi-distantly from and around said central housing for the remainder of said valves, a plurality of studs formed by the intersection 25 of said housings, a resiliently mounted cover plate for the central valve, a plurality of fixed cover plates for the remaining valves, locking and interengaging projections on said fixed cover plates and said central cover 30 plate and means for raising and rotating said central cover plate to rest on the aforesaid studs whereby said projections are disengaged permitting removal of the cover plates, substantially as described.

40 2. In a compression pump, in combination a plurality of ring valves, one of said valves being centrally disposed with respect to the remaining valves that are disposed equi-distantly from and around said central valve, a disc formed with a central housing for said 45

central valve and similar housings disposed equi-distantly from and around said central housing for the remainder of said valves, a plurality of studs formed by the intersection of said housings, a resiliently mounted cover plate for the central valve, a plurality of fixed cover plates for the remaining valves, locking and interengaging projections on said fixed cover plates and said central cover 50 plate means for raising and rotating said central cover plate to rest on the aforesaid studs whereby said projections are disengaged permitting removal of the cover plates, and means for holding, centering and regrinding said ring valves, substantially as 55 described.

3. In a compression pump, in combination, a plurality of ring valves, one of said valves being centrally disposed with respect to the remaining valves that are disposed equi-distantly from and around said central valve, a disc formed with a central housing for said central valve and similar housings disposed equi-distantly from and around said central housing for the remainder of said valves, a plurality of studs formed by the intersection of said housings, a resiliently mounted cover plate for the central valve, a plurality of fixed cover plates for the remaining valves, locking and interengaging projections on said fixed cover plates and said central cover plate, an upwardly projecting screw-stud on said central cover plate, a spanner for engaging said stud, means for raising and rotating said spanner when engaged with said stud, an expansible cylinder for engagement with any one of said ring valves and means for expanding said cylinder and centering said valves, substantially 60 as described.

70 In testimony whereof we affix our signatures.

LEWIS CHEW.
WILLIAM FREDERICK JENNINGS.
